UNITED STATES PATENT OFFICE.

ROBERT O. VANDERCOOK, OF CHICAGO, ILLINOIS.

PROOF PRINTING-PRESS.

1,076,084.

Specification of Letters Patent. Patented Oct. 21, 1913.

Application filed September 9, 1909. Serial No. 516,913.

To all whom it may concern:

Be it known that I, ROBERT O. VANDERCOOK, a citizen of the United States, and a resident of Chicago, in the county of Cook 5 and State of Illinois, have invented certain new and useful Improvements in Proof Printing-Presses, (Case B;) and I do hereby declare that the following is a full, clear, and exact description thereof, reference being had to the accompanying drawings, and to the letters of reference marked thereon, which form a part of this specification.

This invention relates to a novel printing press adapted to take proof impression 15 from forms of type, linotypes, electrotypes or other type forms used with printing presses, and the invention consists of the matters hereinafter described and more specifically pointed out in the appended claims.

20 The invention further relates more particularly to the type of proof printing press described in a patent obtained by me on the 29th day of October, 1912, No. 1,042,848, and especially to an improved construction and 25 arrangement of parts by which the impression member is held down to its work and engagement with the type on the type-bed, in the advance or working movement of said impression-member and is lifted from contact with the type in its backward or return 30 movement. While the invention, as herein shown and described, is embodied in a proof printing press, it will be apparent as I proceed with my specification that it may be 35 incorporated in a regular automatic printing press.

Other improvements are also included in my invention, as hereinafter set forth.

In the drawings Figure 1 is a partial vertical section through my improved printing 40 press; Fig. 2 is a top plan view of the same; Fig. 3 is a partial vertical section through Fig. 2 on line 3—3 thereof; Fig. 4 is a detail view in side elevation of the roller carrying 45 yoke; Fig. 5 is a side elevation of a modified form of said roller carrying yoke.

Referring to the drawings; 1 indicates the bed upon which is supported the type 2 (see Fig. 3) and over which travels the impression-member 3. As only one side of the press is shown in the drawings, the description of the same will be confined to and refer to the one side of the press shown, it being of course understood that the opposite side 55 of the press is identical with the side shown. The impression-member 3 comprises a seg-

mental cylindric shell 4 of relatively large diameter provided at each end with a rocker or support 6. Each rocker is preferably cast integral with said shell. The cylindric 60 rim 7 of said rocker or support 6 is turned to form a bearing surface which engages upwardly facing rail 8 formed at the side of the type-bed 1.

9 indicates a gear secured to the rocker or 65 support 6 and engages a rack 10 secured to the type-bed adjacent the rail 8.

11 indicates a shaft arranged concentrically with the impression-member and rigidly secured thereto. The bed 1 is supported 70 in any convenient manner as, for example, by means of legs (not shown). Mounted upon the end of the shaft 11 is a yoke member 38 consisting of two rigidly connected arms 39^a, 39^b, arranged at an angle to each 75 other, and each of which carries a roller 40 or 41. The yoke member 38 is provided with a long hub 39 journaled on the shaft 11 and having both rotatable and endwise movement thereon. The rollers 40 and 41 are 80 each provided with stub shafts 40^a and 41^a, which are journaled by means of suitable bearings, the one, 40^a by means of suitable roller bearings in the end of the arm 39^a, and the other, 41^a journaled in a box 41^b 85 which is slidably mounted in the end of the arm 39^b. The sliding block 41^b is moved or adjusted by means of an adjusting screw 41^c. Said block 41^b is provided with roller bearings for the stub-shaft 41^a of the roller 41. 90 The adjusting screw 41^c is threaded through a plate 41^d which bridges the bifurcation of the arm 39^b in which the block slides.

Arranged at the side of the bed 1 is a bracket 21^a which is provided on its inner 95 face with a downwardly facing rail 22^a, and also with an upwardly facing rail 22^b, said rails being located in different horizontal planes and in different vertical planes and being separated vertically by a distance 100 slightly less than the diameter of the rollers 40 and 41. The horizontal planes in which said rails are located are both below the level of the axis of the said cylindric impression-member. Said rail 22^a is adapted 105 to engage the tops of the rollers 40 and 41 and through them to hold the impression-member 3 down to its work with the bearing surface 7 of the rocker or support 6 in contact with the track 8, and is of sufficient 110 strength or rigidity to resist the full load in making the impression. At the opposite

ends of the bracket 21^a, the rail 22^a is curved downwardly, as indicated at 23, in such a way as to limit the movement of the rollers 40, 41 when the impression-member is at 5 the opposite limits of its movement.

The hub 39 of the yoke member 38 is reduced in diameter at its outer end to receive a flanged roller 42, which is held from end-wise movement on said hub. At the opposite ends of the bracket 21^a are located cam plates 44, 45, which are adapted to engage the flanges of the roller 42 when the impression-member reaches the opposite ends of its path and shift the yoke member 38 inward 10 or outward in order to cause the rollers 40, 41 to engage with their tops the downwardly facing rail 22^a in the advance or forward movement of the impression-member and to engage with their bottoms, the upwardly 15 facing rail 22^b in the opposite or return movement of the impression member.

The impression-member is provided with an operating arm 25. It is also provided with a tympan 26 which has its opposite 25 ends wound about rollers 27, 27, to which are keyed ratchets 28, 28 adapted to be locked by retaining pawls 29, 29. By means of this construction the tympan may be tightened in its contact with the periphery 30 of the impression-member so as to present a smooth surface to the type.

In this kind of printing press it is essential that the impression-member should be held down to its work with its bearing surfaces in contact with the rails on the type-bed by means of the engagement of the rails 22^a with the rollers 40 and 41 and by reason of the construction described, the yoke member 38 may be adjusted so as to take up any 35 wear in the rollers. It will be apparent that by means of the screw 41^c the roller 41 may be adjusted lengthwise of the arm 39^b of said yoke member 38, which will increase the average distance between the centers of 40 the rollers 40, 41 and the center of the shaft 11.

Instead of the adjustment being made as above described, it may be brought about by means of a construction of a yoke such as 50 illustrated in Fig. 5. In this case the shaft 11 of the impression-member is mounted by means of roller bearings in a block 30 which slides in a slot formed by bifurcations 31, 31, formed in the yoke member 32. The bifurcations are bridged by a plate 33 and the block 30 adjusted in position in the slot by means of a set screw 34. In this case the rollers 35, 36 are each journaled in the ends 55 of the arms 32^a, 32^b of the yoke member 32. 60 This construction provides an arrangement for moving the impression-member back to its initial position, after it has made the impression, in a path above and removed from contact with the type, generally simi-

lar to the construction described in Letters 65 Patent No. 992,461, issued May 16th, 1911, on an application filed by me of even date herewith, in the case of a proof printing press provided with single rollers at the opposite ends of the impression-member. 70

While I have illustrated and described herein certain details of mechanical construction and arrangement, it is to be understood that I do not thereby limit my invention, as it is apparent that they may be 75 modified without departing from the spirit of my invention.

I claim as my invention—

1. A printing press comprising a horizontal type-bed, a rocking, cylindric impression 80 member, supporting rockers on the impression member having curved bearing surfaces concentric with the bearing surface of the impression member, upwardly facing supporting bearing surfaces formed on the bed 85 and adapted to be engaged by the supporting rockers, yokes carried at the ends of said impression member, said impression member having rotative connection with the yokes, with its axis of rotation concentric 90 with said rockers, pairs of rollers carried by said yokes, at least one of the rollers of each pair being laterally shiftable relatively to the impression member, downwardly facing rails located in a plane below the level of 95 the axis of the impression member, upwardly facing rails located in a horizontal plane below the level of said downwardly facing rails and in different vertical planes from 100 said downwardly facing rails, and means for shifting the laterally shiftable rollers into position for engagement in alternation with the downwardly and upwardly facing rails at the opposite limits of the movement 105 of said impression member.

2. A printing press comprising a horizontal type-bed, a rocking, cylindric impression-member, supporting rockers on the impression-member having curved bearing surfaces concentric with the bearing surface of the 110 impression-member, upwardly facing supporting bearing surfaces formed on the bed and adapted to be engaged by the supporting rockers, yokes rotatively carried by said rockers with their axes of rotation coincident with the axes of said rockers, said yokes being movable toward and away from said rockers, pairs of rollers carried by said yokes, a downwardly facing track located in a horizontal plane below the axis of the impression-member and adapted to engage the tops of said rollers in one movement of said impression-member, upwardly-facing tracks located in a horizontal plane below the said 115 upwardly facing tracks and adapted to engage the bottoms of said rollers in the opposite movement of said impression-member, and means for automatically moving 120 125

said yokes to bring said rollers into engagement with either set of said downwardly and upwardly facing tracks.

3. A printing press comprising a horizontal type-bed, a rocking, cylindric impression-member, supporting rockers on the impression-member having curved bearing surfaces concentric with the bearing surface of the impression-member, upwardly facing supporting bearing surfaces formed on the bed and adapted to be engaged by the supporting rockers, yokes rotatively carried by said rockers with their axes of rotation coincident with the axes of said rockers, and said 10 yokes being movable toward and away from said rockers, pairs of rollers carried by said yokes, downwardly facing tracks located in a horizontal plane below the axis of the impression-member and adapted to engage the 15 tops of said rollers in one movement of said impression-member, upwardly facing tracks located in a horizontal plane below the said upwardly facing tracks and adapted to engage the bottoms of said rollers in the opposite movement of said impression-member, and cams located at the opposite ends of the path of said impression-member adapted to move said yokes to bring said rollers into engagement with either set of said downwardly and upwardly facing tracks.

4. A printing press comprising a horizontal type-bed, a rocking, cylindric impression-member, supporting rockers formed on the impression member having curved bearing surfaces concentric with the bearing surface of the impression-member, upwardly facing supporting bearing surfaces formed on the bed and adapted to be engaged by the supporting rockers, yokes provided with hubs,

bearings concentric with said rockers upon which the hubs of said yokes have rotative and endwise movement, pairs of rollers carried by said yokes, downwardly facing rails located in a plane below the axis of the impression-member and adapted to engage the tops of said rollers, upwardly facing tracks located in a plane below the downwardly facing rails and in different vertical planes from those of the downwardly facing rails, and means for shifting said yokes endwise on said bearings at the opposite limits of the movement of said impression-member.

5. A printing press comprising a horizontal type-bed, a rocking, cylindric impression-member, supporting rockers on the impression-member having curved bearing surfaces concentric with the bearing surface of the impression-member, upwardly facing supporting bearing surfaces formed on the bed adapted to be engaged by the supporting rockers, yokes rotatively carried by said rockers with their axes of rotation coincident with the axes of said rockers, pairs of rollers carried by said yokes, one roller of each pair being adjustable with reference to the axis of the yokes, and downwardly facing rails adapted to engage the tops of said rollers, to hold the said impression-member down to its work.

In testimony that I claim the foregoing as my invention I affix my signature in the presence of two witnesses, this 26th day of August A. D. 1909.

ROBERT O. VANDERCOOK.
